UNITED STATES PATENT OFFICE.

ADOLPH WUNDER, OF NEW HAVEN, CONNECTICUT, ASSIGNOR TO SARGENT & CO, OF SAME PLACE.

DESIGN FOR DOOR LATCHES AND HANDLES.

Specification forming part of Design No. **6,537**, dated March 25, 1873.

To all whom it may concern:

Be it known that I, ADOLPH WUNDER, of New Haven, in the county of New Haven and State of Connecticut, have invented a new Design for Door-Handle; and I do hereby declare the following, when taken in connection with the accompanying drawing and the letters of reference marked thereon, to be a full, clear, and exact description of the same, and which said drawing constitutes part of this specification, and represents, in—

Figure 1, a front view of the handle; Fig. 2, a top view of the thumb-piece; Fig. 3, a front view of the guard; Fig. 4, a front view of the socket; Fig. 5, a front view of the latch-bar; and in Fig. 6, the keeper.

This invention relates to a design for the parts of a thumb-latch which may be used individually, in connection with other parts, or collectively.

The form of the handle is shown in Fig. 1, the upper and lower ends affording means of securing the handle to the door, the intermediate part thrown out to form the handle. That part of the thumb-piece upon which the thumb rests is of the form shown in Fig. 2.

The guard-plate has a loop thrown up from a base, through which the latch-bar plays, and is of the form seen in Fig. 3. The socket, into which the end of the latch is pivoted, is of the form seen in Fig. 4, and the latch-bar as seen in Fig. 5, and the keeper as seen in Fig. 6. Each of these parts has a raised edge, giving to the surface a paneled appearance, the surface of the panel matted and ornamented with tracery, as shown in the accompanying illustration.

As either of these parts may be used in connection with other parts than those shown in the accompanying illustration, I, therefore, do not confine my claim to the combination of these several parts; but

I claim as my invention—

The design for door-latch and its several parts, as described, and as shown in the accompanying illustration, whether used collectively or separately.

ADOLPH WUNDER.
